SHEET STACKING MACHINE

Henry W. Lindgren, Pistakee Bay, and Fred H. Nemitz, Waukegan, Ill., assignors to American Can Company, New York, N. Y., a corporation of New Jersey

Application August 27, 1942, Serial No. 456,390

13 Claims. (Cl. 93—93)

The present invention relates to machines for stacking sheet material and has particular reference to arranging the sheets into stacks having a counted predetermined number of sheets in each stack.

An object of the invention is the provision of a sheet stacking machine wherein sheets moving along a conveyor are counted and are arranged into stacks or piles of a predetermined number of sheets so that the sheets may be readily handled for subsequent operations.

Another object is the provision of such a stacking machine wherein the counting and the arranging of the sheets into stacks is effected in a continuous manner and wherein is prevented stoppage or other interference with the progress of the procession of sheets entering the machine for counting and stacking.

Numerous other objects and advantages of the invention will be apparent as it is better understood from the following description, which, taken in connection with the accompanying drawings, discloses a preferred embodiment thereof.

Referring to the drawings:

Figure 1 is a side elevation of a sheet stacking machine embodying the instant invention, with parts broken away;

Fig. 2 is a schematic side elevation of principal parts of the machine showing how the sheets travel through the machine and are stacked;

Fig. 3 is an enlarged transverse section taken substantially along the lines 3—3 in Fig. 1, with parts broken away and parts not shown;

Fig. 4 is a longitudinal section taken substantially along the lines 4—4 in Fig. 3, with parts broken away;

Fig. 5 is an enlarged top plan view of the conveyor section of the machine shown at the right in Fig. 1, with parts broken away;

Fig. 6 is an enlarged horizontal section taken substantially along the line 6—6 in Fig. 1, with parts broken away;

Figs. 7 and 8 are enlarged sectional details taken substantially along the lines 7—7, 8—8 in Fig. 1, with parts broken away;

Figs. 9 and 10 are enlarged details showing electric switch constructions used in the machine, with parts broken away and parts shown in section;

Fig. 11 is an enlarged schematic view showing the operation of high and low stack electric switches used in the machine, with parts broken away and parts shown in section;

Fig. 12 is a part sectional view of the high stack switch used in the machine, with parts broken away;

Fig. 13 is a sectional detail taken substantially along the line 13—13 in Fig. 4, with parts broken away;

Fig. 14 is a horizontal section taken substan-

tially along the line 14—14 in Fig. 13, with parts broken away; and

Fig. 15 is a wiring diagram of the electric apparatus used in the machine, the view showing 5 principal parts of the machine around which the electric apparatus is centered.

As a preferred embodiment of the invention the drawings illustrate a stacking machine in which sheets A (Figs. 1 and 2) of tinplate or the like material are stacked onto a skid B which may be removed manually on a hand truck C when a predetermined number of sheets have been placed in the stack. The sheets are received preferably in a continuously moving procession 10 from any suitable source of supply, such as from a baking oven, a coating machine, a trimming machine or the like.

The sheets A to be stacked, enter the machine on a horizontal endless feed-in conveyor D. 20 While moving along with the conveyor, the sheets are counted by a counting finger E which actuates an electric re-set counting device housed in a cabinet F. Such a counting device may be of the character disclosed in United States Patent 2,087,039, issued July 13, 1937, to A. J. McMaster on Counting system.

As the sheets are counted they are carried to the skid B, which is temporarily located adjacent the discharge end of the conveyor, and are delivered onto the skid to form a stack. The skid while being loaded is supported in an elevator mechanism, generally indicated by the letter H.

The elevator mechanism H while supporting a skid B being loaded with sheets, also carries 30 an empty skid J (see also Fig. 3). This empty skid is located in the upper portion of the elevator mechanism and is supported in an electrically operated holding device K.

At the end of a count, when a predetermined 40 number of sheets to be stacked on the skid B have passed the counting finger E, the counting device in the cabinet F raises a gate L into the path of travel of the sheets. The raised gate diverts the following sheets from the main horizontal conveyor D and guides them onto an auxiliary inclined conveyor M as best shown in Fig. 2.

With the actuation of the gate L a new count for a new stack is started by the counting device. The sheets diverted to the inclined conveyor M are carried by the conveyor to the upper portions of the elevator mechanism and are delivered onto the empty skid J while the loaded skid B is lowered onto the truck C. In this action, the elevator becomes what may be termed a "lowerator." The loaded truck then may be removed to any suitable place of deposit.

After removal of the loaded truck C, a new truck carrying an empty platform N, is wheeled into place in the elevator mechanism. The mechanism is then actuated to raise the empty plat-

form N to the upper part of the machine to receive the skid J then being loaded with sheets. Upon receiving the skid, the platform is lowered to a position just below the level of the main conveyor D, or in other words, in the place previously occupied by skid B. Simultaneously with the shifting of this skid, the gate L is lowered to permit the entering sheets to travel along the main conveyor at the lower level and onto the skid.

During this shifting of the skid to its lower level, the counting of the sheets continues and the delivering of the sheets to the skid continues so that the stack when completed will contain an exact number of sheets. It is during this counting of sheets with the skid J at the lower sheet receiving level formerly occupied by the skid B that a new skid J may be inserted manually in the upper level position.

The main conveyor D comprises a plurality of spaced and parallel, narrow endless belts 21 (Fig. 5) which extend longitudinally of the machine. These belts operate over a plurality of driving pulleys 22 and a plurality of idler pulleys 23 (see also Figs. 1 and 2). The driving pulleys are mounted on a transverse drive shaft 24 while the idler pulleys are mounted on a cross shaft 25.

The shafts 24, 25 are journaled in bearing blocks 26 secured to a pair of spaced and parallel longitudinal beams 27 which constitute a portion of the main frame of the machine. The beams at the entrance end of the machine may be supported on some sheet handling apparatus which as far as the present machine is concerned will constitute the source of supply of the sheets A. At the discharge end of the machine, the beams are supported on pivot pins 31 which are carried in brackets 32 bolted to a pair of inner upright frame legs 33 which together with a similar pair of outer legs 34 constitute the main frame of the elevator and lowerator mechanism H.

The drive shaft 24 of the main conveyor D is rotated by a sprocket 35, which is carried on an outer end of the shaft, and over which an endless chain 36 operates. The chain 36 is driven by a sprocket 38 (Fig. 1) mounted on a driven shaft 39 journaled in a bearing bracket 41 bolted to the floor. The driven shaft 39 carries a sprocket 43 which is rotated by an endless chain 44 actuated by a driving sprocket 45 mounted on a rotor shaft 46 of an electric motor 47. The motor is bolted in place on top of a gear housing 48 secured to a base plate 49 which forms a portion of the machine frame. This motor constitutes the main driving element of the entire machine.

The auxiliary inclined conveyor M is shorter than the main conveyor D and is located above the main conveyor adjacent its discharge end, see also Figs. 2 and 5. This auxiliary conveyor comprises a plurality of spaced and parallel narrow endless belts 52 which operate over a plurality of driving pulleys 53 and idler pulleys 54. The idler pulleys are mounted on a transverse idler shaft 55 journaled in a pair of spaced bearing brackets 56 bolted to the frame beams 27. The driving pulleys 53 are mounted on a drive shaft 57 which is journaled in a pair of spaced bearing brackets 58 bolted to the inner legs 33 of the elevator mechanism H.

The auxiliary conveyor drive shaft 57 is rotated by a sprocket 62 which is mounted on an outer end of the shaft and which is rotated by an endless chain 63 which operates over the sprocket. The chain also operates over a driving sprocket 64 which is carried on the main conveyor drive

shaft 24. In this manner, the two conveyors are actuated in timed relation.

Longitudinal guide rails 65, 66 disposed adjacent the two conveyors D and M, respectively, guide the sheets A in their travel through this portion of the machine. These guide rails are secured to the bearing brackets 26, 56 and 58. Wide and narrow support rollers 67, 68 (Figs. 1 and 5) are disposed adjacent the discharge ends of the two conveyors D and M for supporting the sheets A during their transfer from the conveyors to the skids B and J as hereinbefore mentioned. These rollers are mounted on a pair of vertically aligned cross shafts 69, the ends of the lower shaft being carried in the conveyor drive shaft brackets 26 and the upper shaft being journaled in the brackets 58.

The gate L (Figs. 1, 2 and 5) is located adjacent the lower or entrance end of the auxiliary conveyor M. This gate includes a plurality of spaced and parallel gate arms 71 secured to a transverse pivot or actuating shaft 72. These arms are disposed in pairs arranged one adjacent each outer edge of each of the main conveyor belts 21. The actuating shaft 72 is located below the upper run of the main conveyor D and is carried in bearing brackets 74 bolted to the frame beams 27.

The gate actuating shaft 72 is rocked in its bearings at the proper time by a lever arm 75 which is mounted on the shaft. The outer end of the arm is pivotally connected to a movable core 76 of an electric solenoid 77 bolted to one of the frame beams 27. Normally the solenoid is in a deenergized condition. When in this condition, the usual spring located within the solenoid, holds its core 76 and the connecting lever arm 75 in such a position that the gate arms 71 are substantially horizontal and are disposed below the upper run of the main conveyor D so that the sheets A will travel the full length of this conveyor. It is only when the solenoid 77 is energized, as will be hereinafter described in connection with the description of the wiring diagram, that the gate arms 71 are brought into and are held in the raised position shown in Figs. 1 and 2.

The counting finger E is located adjacent and immediately in front of the gate L, as viewed in Figs. 1 and 5. This counting finger is disposed in the path of travel of the sheets A as they move along on the main conveyor D and is mounted on a cross shaft 78 located below the upper run of this conveyor. Cross shaft 78 is carried in bearing brackets bolted to the frame beams 27. One end of the shaft carries a lever 79 which connects with a movable element of a normally closed electric counting switch 80 bolted to one of the frame beams 27. The finger is held in its normal position in the path of travel of the sheets by a tension spring. One end of the spring is connected to the beam and its opposite end is connected to the lever 79.

Hence as each of the sheets A enter the machine on the main conveyor D, it depresses the counting finger E as it passes by. Depression of the finger opens the switch 80 and this actuates the counting device F which registers one count. Ordinarily the counted sheets pass over the horizontally disposed gate L and travel along the main conveyor D. At the discharge end of the main conveyor, the sheets travel over the lower support rollers 67, 68 and are delivered onto the skid B which is in proper receiving position in the lowerator mechanism H, as hereinbefore explained.

This skid B while being located with sheets

is supported in the elevator or lowerator mechanism H by a plurality of vertically movable lowerator brackets 81 (Figs. 3 and 4). There are four of these brackets located two on each side. The two brackets on each side of the machine are located between the frame legs 33, 34 and are closely adjacent the inner surfaces of the legs. The two brackets of each pair are tied together by two spaced and parallel longitudinal rods 82 and by an angle iron rail 83. The angle iron rail rest in a square notch 84 formed in the inner ends of the brackets. The rails form seats for the opposite ends of the platform N.

Each bracket 81 carries two vertically spaced and aligned rollers 86 which operate in vertical tracks 87 formed in guide rails 88 secured inside of the inner and outer frame legs 33, 34. Each bracket further is secured to the ends of a vertical elevator or lowerator chain 91. There are thus four of these chains 91, located two on each side of the mechanism. These chains operate over pairs of upper and lower sprockets 92, 93.

The upper sprockets 92 are mounted on longitudinal idler shafts 94 (see also Fig. 1) which are carried in bearings 95 bolted to the frame legs. The lower sprockets 93 are the drive sprockets and they are mounted on drive shafts 97. The outer ends of the drive shafts are carried in bearings 98 bolted to the outer legs 34 of the lowerator frame. The inner ends of these drive shafts are carried in bearings 99 (see also Figs. 6 and 8) formed in gear casings 101 which are bolted to the inner legs 33 of the lowerator frame. Thus there is one gear casing on each side of the mechanism.

The drive shafts 97 are adapted for rotation in two directions for raising and lowering the brackets 81 and the platform and skid carrier thereon. For this purpose each shaft 97 carries a bevel gear 105 (Fig. 8) which is housed within its gear casings 101 and which meshes with bevel gears 106. Gears 106 are mounted on the outer ends of a transverse speed reducer shaft 107. Centrally the speed reducer shaft extends through and is rotated by a commercial speed reducer mechanism of suitable construction, there being many types of such on the market. This reducer is housed in a casting 111 mounted on the base plate 49.

The speed reducer mechanism is actuated by a reversing drive shaft 112 (Figs. 6 and 7) which extends through the gear housing 48 and which is carried in bearings 113 formed in opposite ends of the housing. Within the housing the reversing drive shaft carries two loose reversing bevel gears 114 which are located opposite each other and which mesh with one driving gear 115. The driving gear is mounted on the inner end of the machine drive shaft 39 which is continuously rotated by the motor 47.

Between the two loose reversing gears 114, the reversing shaft 112 carries a clutch head 118 which is feathered on the shaft and which is slidable therealong. The ends of the clutch head are formed with teeth 119 which are engageable with teeth 121 in the hubs of the reversing gears 114 when the clutch head is shifted into engagement with one or the other of these gears. Shifting of the clutch head is brought about by an actuating lever 123 which is mounted on a pivot pin 124 carried in the gear housing 48.

The inner end of the lever 123 is formed with a yoke 125 which surrounds the clutch head 118. The ends of the yoke carry head shifting pins 126 which operate in an annular groove 127 78

formed in the clutch head. The outer end of the lever extends through an opening 129 in the gear housing 48 and is pivotally connected to the middle of a link 131. The ends of the link are connected to the cores 132 of two oppositely disposed and normally deenergized electric solenoids 133, 134.

The solenoids 133, 134 are secured to brackets 135 which are bolted to the gear housing 48. Two tension springs 136 located one on each side of the actuating lever 123 hold the latter normally in a neutral position so that the clutch head 118 is out of engagement with both of the reversing gears. The inner end of each of these springs is connected to the lever while each opposite end is attached to a lug 137 formed on each solenoid bracket 135.

Hence when one or the other of the reversing solenoids 133, 134 is energized, its core 132 draws the actuating lever 123 out of its central position and toward the solenoid. This slides the clutch head 118 along the reversing shaft 112 and brings it into engagement with the hub teeth of the opposite reversing gear 114. Engagement of the clutch head with a reversing gear, through the medium of the teeth 119, 121 on these parts, causes the clutch head to revolve in the same direction as the engaged gear. It is this connection that rotates the reversing shaft 112 in the desired direction and through the speed reduction mechanism, rotates the elevator drive shafts 97 in the proper direction and at the proper time to raise or lower the brackets 81, the platform N and a skid.

In the machine shown in the drawings the solenoid 133 is termed the "up-solenoid" and when this solenoid is energized the brackets 81 will move up. Solenoid 134 is the "down-solenoid" and when energized, the brackets will move down.

As the sheets A are delivered to the skid B and are piled in a stack thereon, the skid is lowered a little at a time to keep the top of the stack slightly below the upper run of the conveyor D from which the sheets are delivered. This lowering of the skid is effected by periodically energizing the down solenoid 134 through a high stack electric switch 142 (Figs. 11 and 12). This switch is normally open. The movable element of the switch is engaged by one end of a wire arm 143 which is mounted on a pivot pin 144 carried in a bracket 145 secured to the switch housing. The opposite end of the arm hangs down adjacent and just above the inner edges 55 of the sheets A in the stack on the skid and is held by a tension spring 146 in such a position.

When the pile of sheets becomes high enough to press the arm 143 inwardly against the resistance of the spring 146, the arm closes the switch 142 and thereby establishes suitable circuits connecting with the down solenoid 134. This energizes the solenoid and starts the lowerator mechanism in operation to lower the skid. After this downward movement has once started it is no longer controlled by the switch 142 and the descent of the stack continues after the arm 143 has cleared the top of the stack (Fig. 11) and the switch 142 has opened.

When the skid has moved down a predetermined distance, which preferably is about one inch, the down solenoid is de-energized to stop further down movement of the skid. This stopping of the lowerator is brought about by a normally closed low stack electric switch 149. This low stack switch is actuated by a wire arm 151

which is identical in construction and in operation to the arm 143 on the high stack switch 142. The low stack arm 151 normally engages the edges of the sheets in the stack as shown in Fig. 11 but when the skid moves down far enough, the top of the stack passes below the arm. Thereupon its spring swings the arm outwardly over the top of the stack. This opens the switch 149 and thereby breaks the down solenoid circuit. De-energizing of the down solenoid thus stops further lowerator action.

The high stack and low stack switches 142, 149 are secured to upright guide rails 181 (Figs. 3 and 4) which are fastened to a pair of cross-bars 182 the ends of which are bolted to the inner legs 33 of the lowerator frame. These rails maintain the delivered sheets in a uniform stack with their edges in vertical alignment. The rails cooperate with an aligning or stop plate 184 (see also Fig. 1) which is disposed adjacent the outer legs 34 of the machine frame.

The stop plate 184 is removable and is suspended from a cross-rod 185, the ends of which are carried on serrated upper edges of a pair of horizontal support bars 186 bolted to the frame legs 34. The plate may thus be adjusted into any desired position relative to the stationary guide rails 181 or may be entirely removed if desired. The sheets A as they are discharged from the conveyor D strike against this plate and fall onto the stack on the skid B and are aligned between the plate and the stationary guide rails 181.

At the end of a count, when a predetermined number of sheets A have been counted by the counting finger E, the gate L raises into place to deflect the following sheets up onto the auxiliary conveyor M and these sheets are counted as part of a new series for a new stack, as hereinbefore mentioned. Sheets at the tail end of the old series and still on the conveyor D beyond the gate L, are delivered to the stack on the skid B to complete the stack. There is thus a predetermined counted number of sheets in the stack.

In the instant machine each stack preferably consists of eleven hundred twenty sheets, this being an even multiple of base boxes of ordinary plate used in can manufacture. When the eleven hundred twentieth sheet is counted, the gate L lifts to divert the eleven hundred-twenty-first sheet. Such a diverted sheet becomes number one for the next stack beginning to form on the empty skid J at the discharge end of the auxiliary conveyor M. Thus there is no stopping of the machine at the end of a count and this permits of continuous feeding of the sheets from the source of supply.

While this new stack is forming on the upper skid J, the loaded skid B is lowered onto the truck C by actuation of the lowerator through a further energizing of the down solenoid 184. Energizing of the down solenoid for this purpose is effected manually by the closing of a normally open push button switch 169 (Fig. 15). When the loaded skid reaches the truck a limit switch 170 (see also Fig. 1) is actuated by a pin 172 secured to one of the chains 91. Actuation of this switch deenergizes the down solenoid and thus stops the lowerator.

With the lowerator in this position, the loaded truck C is removed to any suitable place of deposit and is replaced with another truck C carrying an empty platform N. When the new truck is fully in place, the elevator lowerator mechanism is set in motion through an upward

movement during which the brackets 81 pick up the empty platform N and carry it up into engagement with the upper skid J which is being loaded with sheets from the auxiliary conveyor M. This upward movement of the elevator is brought about by manual closing of a normally open push button switch 174 (Figs. 1 and 15). Closing of this switch energizes the up-solenoid 183 which controls the rotation of the drive shafts 91 for the ascension.

When the empty platform N reaches the loading skid J the elevator is stopped by actuation of a limit switch 176 (Figs. 3 and 15). The switch is tripped by a pin 177 which is secured to one of the chains 81. Actuation of the switch de-energizes the up-solenoid and it is this action that stops the up travel of the elevator and the platform N carried thereon.

The upper skid J which it will be recalled was positioned by hand above the lowered skid receiving the counted sheets, is supported on a pair of angle iron rails 185 (Figs. 3, 4 and 13). These rails extend longitudinally of the elevator mechanism along two sides thereof between the inner and outer frame legs 33, 34. These rails are directly above the brackets 81 when the latter are in raised position. Each rail 185 is secured to a pair of spaced and parallel depending holding arms 186 which form parts of the holding device K.

There are four holding arms 186 in all, two on each side of the elevator mechanism. Each pair of arms is mounted on a longitudinal shaft 187 which is carried in a pair of bearing blocks 188. The bearing blocks are formed on long sleeves 189 which extend at right angles to the bearing blocks, i. e., transversely of the machine. These sleeves fit tightly onto a pair of spaced and parallel rods 191 which extend across the top of the elevator mechanism. The ends of the rods 191 are secured in bosses 192 formed in longitudinal tie beams 193 which are bolted to the tops of the inner and outer frame legs 33, 34 (see Fig. 1).

Sheets A delivered from the auxiliary conveyor M to the skid J supported by the holding arms 186, are guided into stack formation by a pair of hanging side guide plates 194 (Figs. 3, 4 and 13), by inner stationary vertical guide rails 195, and by an outer hanging stop plate 186. The side guide plates 194 are bolted to lugs 197 which are formed on the bearing blocks 188. These plates 194 are formed with depending narrow extensions 198 which hang down through slots 199 (Fig. 13) in the skid support rails 185. This assists in guiding the sheets into place on the skid. Plates 194 may be slotted vertically, as at 201, Fig. 4, to permit adjustment relative to the lugs 197.

The stationary guide rails 195 are secured to a cross-bar 202 which is bolted to the inner frame legs 33. These guide rails are shorter than the guide rails 181 and are located above and in spaced relation to the latter to permit discharge of the sheets A from the main conveyor D. The rails 195 and 181 are in vertical alignment so that the edges of the sheets in the stack on the skid J will be kept in line when the skid is moved down subsequently to receive sheets from the main conveyor D.

The stop plate 186 is identical in its use with the stop plate 184 but is shorter in length. This stop plate is secured to a cross-bar 203, the ends of which are supported on upper serrated edges of a pair of short support bars 204 bolted to the

outer frame legs 34. This plate therefore is like lower stop plate 184 in being removable and normally is suspended in alignment with the lower plate.

When the empty platform N engages against the bottom of the skid J at the top of the up travel of the platform, as hereinbefore mentioned and as best shown in Fig. 3, it lifts the skid slightly so that the weight is taken off the skid support arms 186. While the skid is thus supported on the platform the skid support arms 186 are rocked outwardly away from the skid and this releases the skid. This is a momentary action and is effected as soon as the platform reaches the top of its up travel. At the termination of the up travel the control switch 176 is engaged by the pin 177 on the elevator chain. This operates the switch and immediately energizes the down solenoid 184. The lowerator brackets 81 with the platform N and with the loaded skid J thereupon starts moving through a downward travel toward the main conveyor D.

Rocking of the skid holding arms 186 to release the partly loaded skid J is brought about by a pair of normally deenergized holding solenoids 211 (Figs. 1, 3 and 4). These solenoids are supported in vertical position on two pairs of longitudinal beams 212 secured to bosses 213 formed on the long sleeves 189. Each solenoid is provided with a movable core 215 which extends down from the bottom of the solenoid. The lower end of each core is connected by a link 216 to the inner end of a lever 217. Each lever is carried on a skid arm shaft 187. There are two of these levers, one for each skid arm shaft as best shown in Fig. 3.

When the holding solenoids 211 are energized their cores 215 are pushed down, as viewed in Fig. 3 and this movement rocks the levers 217, the skid arm shafts 187 and the skid holding arms 186. This is the way in which the skid J is released. Springs housed within the solenoids and the weight of the skid arms and their support rails 185 return the arms to their original position when the solenoids are deenergized. This deenergizing of the solenoids takes place soon after the skid J starts to move down and while loading of the skid continues. It is when the holding arms are again in their original position following such movement, that a new empty skid J is inserted in readiness for the next stack.

The descending lowerator brackets 81 carrying the partly loaded skid J on the platform N comes to rest when the skid J is slightly below the upper run of the main conveyor D. For a better understanding of this action the skid may be considered to be a skid B as soon as it has been brought down. Then it is ready to receive sheets from the conveyor D to complete its stack.

It should be understood that this transfer of the skid from the upper level to the lower level is effected to prevent stopping of the machine at the end of a count so that continuous operation may be had while maintaining an accurate count of the sheets piled in each stack. It is only at the beginning of the count that the sheets are diverted onto the auxiliary conveyor M and are carried by this conveyor to the skid when it is in the holding device K.

Just before the descending skid comes to rest at the end of a count, the gate L is lowered by the deenergizing of its solenoid 77. This stops the diverting of the sheets to the auxiliary conveyor M and permits the sheets to pass normally

along the conveyor D so that they may be delivered to the skid now considered as skid B, at the lower level. Lowering of the gate is brought about by the opening of a normally closed gate switch 221 (Figs. 3 and 10) which is secured to one of the lowerator frame legs 33.

The switch 221 is provided with a movable element 222 which is engaged by a lug 223 formed on a disc 224 mounted on a pivot pin 225 carried in a bracket 226 formed on the box which contains the switch. The lug is held against the movable element by a spring which is stretched between the lug and the bracket 226. The disc carries a finger 227 which is mounted on a pivot pin 228 secured in the disc. The inner end of the finger is held by a tension spring 229 against a stop pin 230 which is secured in the disc. One end of the spring is connected to the finger while the opposite end is fastened to the disc. The outer end of the finger extends beyond the disc in the path of travel of a trip pin 232 carried by one of the elevator, lowerator chains 81.

Hence as the chains 81 move the loaded skid J down into its lower level position, the trip pin 232 carried on an ascending run of the chain, engages the projecting end of the finger 227 and thus through the stop pin 230 rotates the disc 224 in a counter-clockwise direction, as viewed in Fig. 10. Rotation of the disc in this direction brings its lug 223 down against the movable element 222 of the switch 221 and thus opens the switch. This is a momentary action which is effected as the trip pin passes the switch finger.

On an up travel of the elevator and while the trip pin 232 is moving down, the pin engages against the finger 227 and rocks it on its pivot 228 in a clockwise direction against the resistance of the spring 229 but does not rotate the disc. The switch 221 therefore is not operated during such time but remains in its closed condition.

Reference should be had to the preceding description of the lowering of the skid J by the closing of the switch 142. When the skid J comes into position at its desired lower level, the lowerator mechanism is brought to rest by the opening of a normally closed stop switch 236 (see Figs. 1 and 9). This switch is actuated by a trip pin 237 carried on an adjacent lowerator chain 81. The switch is secured to one of the outer frame legs 34. The switch box is formed with a bracket 238 which carries a pivot pin 241 on which a disc 242 is mounted. The disc is formed with a lug 243 which engages the movable element of the switch. Adjacent the chain, the disc is formed with a notch 245.

On the down travel of the lowerator, the trip pin 237 which is carried on the upwardly moving run of the chain moves past the disc 242 and engages in the notch 245 of the disc. This rising pin thus rotates the disc in a counter-clockwise direction, as viewed in Fig. 9. This presses the disc lug 243 down against the movable element of the switch and opens the switch. It is this action that stops the lowerator, as hereinbefore mentioned.

A detent device holds the disc 242 in a shifted position. This device includes a spring barrel 246 which is disposed in a block 247 formed as a part of the bracket 238. The outer end of the barrel is pointed and fits into a stop notch 248 formed in the periphery of the disc. The detent holds the switch open when the disc is moved into this position.

On an up travel of the elevator, the trip pin

237 moves down and while passing the disc 242, again engages into the notch 245 and rotates the disc in a clockwise direction. This rotation of the disc lifts its lug 243 off the movable element of the switch and thus permits the switch to close. The detent spring barrel engages into a notch 249 following this partial rotation and thus holds the disc stationary while the switch remains closed.

Reference should now be had to the wiring diagram in Fig. 15. As hereinbefore explained, each sheet A as it enters the machine, trips the counting finger E and thus opens the electric counting switch 80, shown at the right in the diagram. One side of this switch is connected by a wire 301 to a main lead wire 302 which leads from a suitable source of electric energy such as a generator 303. The other side of the switch is connected by a wire 304 to a suitable recycling or self-setting electric counter 305 which may be of the character disclosed in the above mentioned McMaster patent. The counter is also connected by a wire 306 to a main lead wire 308 which joins with the generator.

As shown in the diagram this counting circuit is a normally closed circuit so that electric energy passes through the counter. Every time a sheet A depresses the counting finger E and thus opens the switch 80, the circuit is broken and the counter counts one sheet. When a predetermined number of sheets have been counted, in accordance with the setting of the counter, a relay circuit a is established momentarily. This is at the end of a count and establishes three new cooperating circuits b, c, d which raise the gate L into its sheet diverting position.

At the end of the count, the counter 305 energizes a solenoid 311 which is part of a normally open relay switch 312. One side of the solenoid is connected by a wire 313 to the counter. The other side of the solenoid is connected by a wire 314 to the generator lead wire 302.

Hence at the end of a count, electric energy from the generator travels along main lead wire 308, wire 306, through the counter 305, wire 313, relay solenoid 311, wire 314, and main lead wire 302 back to the generator. Energy traveling along this circuit energizes the solenoid 311 and this closes the switch 312. This is only a momentary action, since the counter immediately re-sets itself and begins counting the next sheet which follows. This next sheet is number one in a new count for a new stack of sheets.

However, the momentary closing of the switch 312 establishes the circuit b which includes a relay solenoid 320. One side of the switch is connected by a wire 321 to the generator lead wire 302, while its opposite side is connected by a wire 322 to the relay solenoid. The solenoid is also connected by a wire 323 to the generator lead wire 308. Electric energy passing along this circuit b while the switch 312 is closed, energizes the solenoid.

Energizing of the relay solenoid 320 closes two normally open switches 325, 326 which are included respectively in the circuits c and d. Circuit c is a holding circuit for holding the solenoid 320 energized after the switch 312 opens. This circuit includes the gate control switch 221, hereinbefore mentioned. One side of the gate control switch 221 is connected by a wire 328 to the generator wire 302. The other side of the gate control switch is connected by a wire 329 to the now closed switch 325. Switch 325 also is con-

nected by a wire 331 to the coil of the solenoid 320 at the junction with the wire 322.

Hence when both of the switches 221 and 325 are closed, electric energy from the generator lead wire 302, passes along wire 328, closed gate switch 221, wire 329, closed switch 325, wire 331, solenoid 320, wire 323, to the generator lead wire 308. This circuit holds the solenoid 320 energized until the gate control switch 221 is opened by the lowering of the lowerator mechanism when bringing a partially filled skid into position at its lower counting level as hereinbefore explained.

Closing of the relay switch 326 by the energizing of the solenoid 320, establishes the circuit d which includes the gate solenoid 17. One side of the switch is connected by a wire 335 to the generator lead wire 308. The opposite side of the switch is connected by a wire 336 to the solenoid. The solenoid also is connected by a wire 337 to the generator lead wire 302.

Electric energy passing along this circuit d when the switch 326 is closed energizes the gate solenoid 17 and thus raises the gate L into sheet diverting position. As long as the solenoid 320 remains energized, the gate solenoid 17 remains energized and thus the gate is held in sheet diverting position until the gate control switch is opened as mentioned above.

Raising of a truck platform N to the top of the 30 elevator mechanism H to pick up the skid J which is being loaded with sheets at the beginning of a count, is brought about through the establishment of a circuit e which includes the normally closed limit switch 170 and the normally open push button switch 174. In this circuit the movable element of the limit switch 170 is connected by a wire 341 to the generator lead wire 308.

In its normal position, the movable element 40 of the switch 170 engages a contact 342 which is connected by a wire 343 to one side of the push button switch 174. The opposite side of the button switch is connected by a wire 344 to a relay 45 solenoid 345. The solenoid also is connected by a wire 346 to the generator lead wire 302. Hence when the button switch is closed momentarily, electric energy passes along this circuit e and energizes the relay solenoid 345.

Relay solenoid 345 controls four switches, two normally open switches 348, 349 and two normally closed switches 351, 352. Closing of the normally open switch 348 establishes a holding circuit f which includes the normally closed limit switch 55 176 and which temporarily holds the solenoid 345 in an energized condition.

In this holding circuit f, the movable element of the limit switch 176 is connected by a wire 355 to the generator lead wire 308. Normally the 60 movable element of the limit switch engages a contact 356 which is connected by a wire 357 to one side of the relay switch 348. The other side of the relay switch is connected by a wire 358 to the solenoid 345 at the junction with the wire 344.

Hence when the relay switch 348 closes, electric energy from the generator lead wire 308 passes along the circuit, through the solenoid 345 70 and back along the wire 346 to the generator lead wire 302. This circuit cuts out the push button switch 174 and the limit switch 176 and thus keeps the solenoid 345 in an energized condition after the push button is released and the switch 75 opened.

Closing of the relay switch 349 which is effected simultaneously with the closing of the switch 348 just described, establishes a circuit *g* which operates the elevator mechanism through an accelerated or rapid travel. This up-fast circuit *g* includes the up-solenoid 133 of the elevator actuating devices.

In the up-fast circuit *g* one side of the up-solenoid 133 is connected by a wire 381 to the generator lead wire 308. The other side of the solenoid is connected by a wire 382 to one side of the closed relay switch 349. The switch also is connected by a wire 383 to the generator lead wire 302. Electric energy passing along this circuit energizes the up-solenoid 133 and this in turn shifts the clutch head 118 of the elevator actuating devices into mesh with the proper gear 114 and thus rotates the shafts 112, 107, 91 in the proper direction, as hereinbefore described. This action operates the elevator on an upward travel.

As soon as the elevator begins to move up, the switch operating pin 172 on one of the chains 91, moves away from the movable element of the limit switch 170. This permits the usual spring located within the switch to shift its movable element away from the contact 342. This opens the circuit *e*. This action also brings the movable element of the switch 170 into engagement with a contact 365 preparatory to the establishment of new circuits which will be hereinafter described.

When the elevator reaches the top of its up travel and brings the truck platform into engagement with the skid J, the switch operating pin 177 (see also Fig. 3) on the chain 91, engaging the movable element of the limit switch 176 and shifts it away from the contact 356. This opens the switch and breaks the solenoid holding circuit *f*.

Breaking of the holding circuit *f* de-energizes the solenoid 345 and this opens the two closed relay switches 348, 349. It also recloses the two normally closed relay switches 351, 352. These two latter switches 351, 352 were opened merely during the establishment of the holding circuit *f* and of the up-fast circuit *g*. Such a provision safeguards other circuits and prevents accidental establishment thereof during the up-travel of the elevator. Opening of the relay switch 349 breaks the up-fast circuit *g* and thus de-energizes the up-solenoid 133 stopping elevator travel.

It will be remembered that when the elevator reaches the top of its travel, the skid arms 186 release the skid J and permit its settling onto the raised platform N. This is brought about by the actuation of the limit switch 176 which has just been opened by the shifting of its movable element away from the contact 356. In shifting, the element comes into engagement with a new contact 366. This establishes a skid release circuit *h*.

In this skid release circuit *h*, the contact 366 is connected by a wire 371 to the coils of a solenoid 372 of a relay 373. The solenoid is connected by a wire 374 to the generator lead wire 302. Electric energy from the generator lead wire 308 passing along this circuit by way of the wire 355, switch element 176, and contact 366, energizes the relay solenoid 372.

When the relay solenoid is energized it closes the relay 373. One side of relay 373 is connected by a wire 376 to the generator lead wire 308. The other side is connected by a wire 377 to one end of each of the two skid release solenoids 211. The opposite ends of solenoids 211 are connected by wires 378, 379 to the generator lead wire 302.

Hence when the relay 373 is closed, energy from the generator lead wire 302 passes through the skid release solenoids 211 and energizes them. It is this action that rocks the skid arms 186 outwardly and thus releases the partially loaded skid J so that it will be picked up and then will be handled by the raised platform N.

Simultaneously with the releasing of the skid J, the lowerator starts down and carries the platform N and its skid J to the lower level to receive sheets from the main conveyor D. This downward movement of the lowerator begins as soon as it reaches the peak of its up travel and is started by the breaking of the holding circuit *f* which deenergizes the solenoid 345 and closes the relay switch 351. This lowering of the skid J is effected through an accelerated or rapid descent circuit which may be termed "a down-fast circuit *j*." Such a circuit includes the down solenoid 134. Associated with circuit *j* is a low level circuit *k* which includes the low level stop switch 236.

In the low level circuit *k*, electric energy passes from the generator lead wire 308 along wire 341, the movable element of the control limit switch 170, contact 365, a connecting wire 381, closed low level stop switch 236, a connecting wire 382, a solenoid relay 383, and a wire 384 connecting with and returning to the generator lead wire 302. Energy passing along this circuit energizes the solenoid relay 383 and thus closes a relay switch 385 against a pair of contacts 386, 387. These contacts 386, 387 form a part of the down-fast circuit *j*.

When down-fast circuit *j* is established electric energy passes by way of the wire 341, switch element 170, contact 365, a connecting wire 381, closed relay switch 351, a connecting wire 382, contact 386, closed switch 385, contact 387, a connecting wire 393, down solenoid 134 and thence by way of a return wire 394 back to the generator lead wire 302. This energizes the down solenoid 134. Energizing of this solenoid shifts the clutch head 118 (see also Fig. 7) into engagement with the proper gear 114 of the lowerator actuating mechanism and thus rotates the connecting shafts to produce the desired descent of the lowerator.

As soon as the skid J begins to move down, the switch actuating pin 177 (see also Fig. 3) on the lowerator chain 91 moves away from the movable element of the limit switch 176 whereupon the switch element shifts from the contact 366 to the contact 356. This breaks the skid release circuit *h* and thus de-energizes the skid release solenoids 211. The skid arms 186 thereupon return to their original positions in readiness for the reception of any empty skid which will be manually placed as already fully described. The shifting of the switch element into engagement with the contact 356 also partially re-sets the holding circuit *f* in readiness for subsequent work.

As the skid J approaches its lower level adjacent the discharge end of the main conveyor D, the gate switch actuating pin 232 (see also Figs. 3 and 10) on one of the lowerator chains 91 trips the gate control switch 221, as hereinbefore explained. Tripping of this switch lowers the gate L to cause the incoming sheets to travel along the main conveyor D.

Immediately following the tripping of the gate control switch 221 at which time the skid J arrives in place at its lower level, the stop switch 236 (see also Fig. 9) is opened by its actuating pin 237 on the adjacent lowerator chain. Opening

of this stop switch breaks the stop circuit *k* and thereby de-energizes the solenoid relay 383 in this circuit. This action moves the relay switch 385 to break the down-fast circuit *j*, between the contact points 386 and 387. Thus the down solenoid 134 is deenergized and the lowerator stops. This movement of the relay switch 385 causes it to close with a pair of contacts 388, 397 of a jog circuit *m* which will now be described.

When the skid is once in position adjacent the discharge end of the main conveyor D, its further downward movement is controlled by the high stack switch 142 and the low stack switch 148 as has been described in connection with Fig. 11. These switches cooperate in jogging the skid down a short distance at a time as the sheets A are delivered so that the top of the stack will be maintained slightly below the discharge level of the main conveyor.

As each sheet A is delivered into place on the stack it strikes the wire actuating arm 143 of the high stack switch 142 and momentarily closes the switch. In order to prevent each such momentary closing of the switch from completing the jog circuit *m* and from setting up an erratic action, a slow-closing, quick-opening time delay device 401 is included in the circuit. The delay device includes a solenoid 402 which operates a normally open relay switch 403. The retarding action of the device 401 negatives any momentary switch closing and opening of the high stack switch from actuating the relay switch 403.

When the pile of sheets on the skid being loaded is high enough to hold the high stack switch 142 closed, the time delay solenoid 402 is energized and this slowly closes the relay switch 403. Energizing of the time delay solenoid is effected by electric energy which passes from the generator lead wire 308, along the wire 341, switch element 170, contact 365, a connecting wire 408, closed high stack switch 142, delay solenoid 402 and a connecting wire 406 returning to the generator lead wire 302.

When the relay switch 403 closes, the jog circuit *m* is established. In this circuit energy from the generator lead wire 308, passes along wire 341, switch element 170, contact 365, wire 405, the closed low stack switch 148, a connecting wire 408, closed relay switch 403, a connecting wire 409 which leads to the closed switch 352, through that switch, a wire 411, contact 386, closed relay switch 385, contact 397, a connecting wire 412, a solenoid 413, and a connecting wire 414 back to the generator lead wire 302.

Energy passing along this circuit *m* energizes the solenoid 413 which in its turn closes two connecting relay switches, a holding switch 417, and a down-switch 418. The holding switch 417 is connected by a wire 421 to one side of the low stack switch 148. On the other side, the holding switch is further connected by a wire 422 to one side of the relay switch 352. These connections cut out the time delay switch 403 so that when it opens, the circuit *m* will still be maintained by the connections just described.

The down-switch 418 is connected by a wire 425 to the generator lead wire 308 and by a wire 426 to the down solenoid 134. Thus when this switch is closed the down solenoid is energized and the lowerator actuating mechanism thereupon lowers the skid and the stack of sheets carried thereon. When the top of the stack reaches a level where it releases the wire arm 151, the low stack switch 148 opens as hereinbefore mentioned. This breaks the holding cir-

cuit and the down-jog circuit which are controlled by the relay switches 417, 418 and the lowerator thus stops.

When the sheets delivered to the stack again build up sufficiently to again operate the high stack switch 142, the above described circuits are reestablished and the skid again moves down to permit the building up of the stack. In this manner the skid is repeatedly jogged down until the end of the count is reached and until the delivery of sheets to this particular stack is completed.

At the end of the count, the loaded skid is ready to be moved down onto a truck C which in the meantime has been placed in the lowerator. This lowering of the skid is brought about by manual closing of the push button switch 169. One side of this push button is connected by a wire 428 to the contact 365 of the limit switch 170. The other side of the button switch is connected by a wire 429 to the solenoid 383 which, it will be recalled, controls the relay switch 385.

By closing the push button switch 169, electric energy from the generator lead wire 308 passes along wire 341, switch element 170, contact 365, wire 428, closed push button 169, wire 429, solenoid 383, wire 384, returning to the generator lead wire 302. This energizes the solenoid 383 which then shifts the movable element of the switch 385 into engagement with the contacts 386, 387 of the down-fast circuit *j*. This reestablishes the down-fast circuit *j* and the down solenoid 134 is energized, bringing the lowerator actuating devices into play and moving the loaded skid down onto its truck.

The push button switch 169 must be held closed until the loaded skid is deposited on the truck, and when the skid reaches the truck, the lowerator is automatically stopped. This is brought about by the switch control pin 172 which it will be recalled, is carried on the lowerator chain 91 adjacent the limit switch 170. At the bottom of the down travel of the lowerator, the pin 172 shifts the movable element of the switch 170 away from the contact 365 and returns it into engagement with the contact 342. This breaks those circuits connecting with contact 365 and partially restores those connecting with contacts 342. This sets the elevator, lowerator mechanism in proper condition to repeat the entire process as just explained, for the next stack which is loading on a skid J in the skid holding devices K.

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

We claim:

1. In a sheet counting and stacking machine, the combination of a counting device for counting individual sheets as they are received from a source of supply, means for holding a skid in position to receive a predetermined number of sheets as they are being counted, said skid with the sheets being removable from the machine when loaded, means for holding an auxiliary skid adjacent the skid on which the counted sheets are being received, means operable by said counter when the predetermined number of

sheets have been counted for stopping the delivery of sheets to said loaded skid and for transferring delivery of the following sheets to said auxiliary skid, means for shifting said auxiliary skid with the sheets received thereon into the place of said loaded skid while the latter is being removed from the machine and without interruption of the counting of sheets, and means for restoring said auxiliary skid holding means as an incident to placing a new auxiliary skid in position for the reception of sheets at the end of the count when the skid being loaded has received its predetermined number of sheets.

2. In a sheet counting and stacking machine, the combination of means for counting sheets moving along a predetermined path of travel in a continuous procession, a main conveyor for advancing the counted sheets, means adjacent said conveyor for supporting a skid for receiving the counted sheets to form a stack, said skid being removable from its position adjacent said conveyor when a stack of a predetermined number of sheets has been deposited thereon, an auxiliary conveyor adjacent said main conveyor, a gate between said conveyors and operable by said counting means for diverting counted sheets from said main conveyor to said auxiliary conveyor so that interruption of the progress of the sheets will be prevented at the end of a count for one stack and the starting of a count for a new succeeding stack, means adjacent said auxiliary conveyor for supporting an empty auxiliary skid for receiving the sheets diverted thereto to form a new stack while the completed stack is being removed from the machine, mechanism for shifting said auxiliary skid on which said new stack is being formed into position adjacent said main conveyor to take the place of the loaded removed skid, and devices for shifting said gate with the shifting of said auxiliary skid so that the counted sheets will travel along said main conveyor for delivery to said auxiliary skid to complete the stack while maintaining an accurate and continuous count of the sheets in the stack.

3. In a sheet counting and stacking machine, the combination of a counting device for counting individual sheets as they are received from a source of supply, a vertically movable elevator disposed in spaced relation to said counting device and carrying a skid for receiving a predetermined number of sheets as they are individually counted and for holding them in stacked order, a holding mechanism located above said elevator for retaining an empty auxiliary skid, means operable by said counter when the predetermined number of sheets has been counted for stopping the further delivery of sheets to said loaded skid and for transferring following sheets to the empty auxiliary skid to begin the forming of a new stack thereon, means for removing said loaded skid from the machine, and actuating devices for operating said elevator to deposit the loaded skid onto said removing means and to shift said auxiliary skid into position at the place vacated by said loaded skid to receive sheets for the completion of its stack.

4. In a sheet counting and stacking mechanism, the combination of a counting device for counting individual sheets as they are received from a source of supply, a main conveyor for advancing the counted sheets, an auxiliary conveyor disposed at a level above said main conveyor, a gate between said conveyors for diverting counted sheets from said main conveyor to the higher level, a vertically movable elevator disposed adjacent the

outer ends of said conveyors, means above said elevator for supporting a skid for initially receiving counted sheets from said auxiliary conveyor, actuating means for operating said elevator to pick up the skid at the upper level of the auxiliary conveyor and to carry it down to the lower level of the main conveyor to receive sheets therefrom for the completion of the stack while an empty skid is being placed at the upper level for a subsequent stack, and devices operable by said elevator when the skid reaches the lower level for shifting said gate from the auxiliary conveyor to the main conveyor so that sheets will advance along the main conveyor for delivery onto the stack.

5. In a sheet counting and stacking mechanism, the combination of a counting device for counting individual sheets as they are received from a source of supply, a main conveyor for advancing the counted sheets, an auxiliary conveyor disposed at a level above said main conveyor, a gate between said conveyors for diverting counted sheets from said main conveyor to the higher level, a vertically movable elevator disposed adjacent the outer ends of said conveyors, means above said elevator for supporting a skid for initially receiving counted sheets from said auxiliary conveyor, actuating means for operating said elevator to pick up the skid at the upper level of the auxiliary conveyor and to carry it down to the lower level of the main conveyor to receive sheets therefrom for the completion of the stack while an empty skid is being placed at the upper level for a subsequent stack, instruments connecting with said skid supporting means and operable by said elevator for releasing the skid so that it can be picked up by said elevator, and devices operable by said elevator when the skid reaches the lower level for shifting said gate from the auxiliary conveyor to the main conveyor so that sheets will advance along the main conveyor for delivery onto the stack.

6. In a sheet counting and stacking mechanism, the combination of a counting device for counting individual sheets as they are received from a source of supply, a vertically movable elevator disposed in spaced relation to said counting device, movable support arms located above said elevator for retaining a skid for the reception of the counted sheets, electric solenoids connecting with said support arms for controlling their operation, actuating means for operating said elevator to shift the skid from one level to another to receive a predetermined number of sheets, and electric means operable by said elevator for actuating said solenoids and through them said support arms to release the skid so that it may be shifted by said elevator.

7. In a sheet counting and stacking mechanism, the combination of a counting device for counting individual sheets as they are received from a source of supply, a vertically movable elevator disposed in spaced relation to said counting device, a holding mechanism located above said elevator for retaining a skid adapted to receive the counted sheets, a reversing gear mechanism for actuating said elevator upwardly to receive the skid from said holding mechanism and downwardly to lower the skid to a lower feed level for the reception of a predetermined number of sheets, a pair of electric solenoids connecting with said reversing gear, one of said solenoids being arranged to control the up travel of said elevator and the other the down travel, and electric switches connecting with said solenoids to control their operation.

8. In a sheet counting and stacking mechanism, the combination of a counting device for counting individual sheets as they are received from a source of supply, a vertically movable elevator disposed in spaced relation to said counting device, a holding mechanism located above said elevator for retaining a skid adapted to receive the counted sheets, a reversing gear mechanism for actuating said elevator upwardly to receive the skid from said holding mechanism and downwardly to lower the skid to a lower feed level for the reception of a predetermined number of sheets, a pair of electric solenoids connecting with said reversing gear, one of said solenoids being arranged to control the up travel of said elevator and the other the down travel, electric switches connecting with said solenoids to control their operation, and a pair of high and low stack electric switches operable by a stack of sheets on said skid while at said lower feed level and connecting with the electric solenoid that controls the down movement of the elevator for periodically lowering the elevator and the skid carried therein in time with the building up of the stack of sheets on the skid so that the top of the stack will always be in a proper position to receive the counted sheets as they are delivered onto the stack, one of said stack switches being utilized to start the lowering of the elevator and the other to control the stopping of the elevator.

9. In a sheet counting and stacking machine, the combination of a counting device for counting individual sheets as they are received from a source of supply, vertically movable means for supporting a main skid member in position to receive a predetermined number of sheets as they are being counted, said skid with its counted sheets thereon being removable from the machine, means on said machine for holding an auxiliary skid member in variable spaced relation to said main skid member on which the counted sheets are being received, and main and auxiliary conveyor means selectively controlled by said counting device for respectively and successively delivering counted sheets to be stacked to said main and auxiliary skid members during vertical movement of said vertically movable means, whereby to insure against interruption of the counting of the sheets and also while a said loaded skid member is being removed from the machine.

10. In a sheet counting and stacking machine, the combination of means for counting sheets moving along a predetermined path of travel in a continuous procession, a main conveyor for advancing the counted sheets, vertically movable means disposed adjacent said conveyor for supporting a main skid member while the latter is receiving the counted sheets to form a stack, said skid being designed to be removed from its position adjacent said conveyor when the stack of a predetermined number of sheets has been deposited thereon, an auxiliary conveyor disposed adjacent said main conveyor, a gate located between said conveyors and operable by said counting means for diverting counted sheets from said main conveyor to said auxiliary conveyor at the end of a predetermined count and without interruption of the sheet travel, said vertically movable means being also disposed in variable spaced relation to said auxiliary conveyor and cooperating with means on said machine for supporting an empty auxiliary skid member designed for receiving the sheets diverted from said main conveyor for a new counted sheet stack while the completed and counted stack on said main skid

5 member is being removed from the machine, and means for vertically moving said main skid member supporting means during counting of the sheets being deposited upon said skids, whereby to insure against interruption in the continuous counting of said sheets.

11. In a sheet counting and stacking machine, the combination of a counting device for counting individual sheets as they are received from a source of supply, a vertically movable elevator disposed in spaced relation to said counting device for supporting a main skid member for receiving a predetermined number of sheets as they are individually counted and for holding them in stacked order, a holding mechanism located in the machine above said elevator and operable in timed relation with the latter for supporting an empty auxiliary skid member in variable spaced relation to said main skid member, means for vertically moving said elevator in timed relation to the delivery of counted sheets to said main and auxiliary skid members, and main and auxiliary conveyor means selectively controlled by said counting device for respectively and successively delivering counted sheets to be stacked to said main and auxiliary skid members.

12. In a sheet counting and stacking machine, the combination of a counting device for counting individual sheets as they are received from a source of supply, a vertically movable elevator disposed in spaced relation to said counting device and supporting a main skid for receiving a predetermined number of sheets as they are individually counted and for holding them in stacked order, actuating means for said elevator for periodically shifting the supported skid from an upper level to a lower level in timed relation with the building up of counted sheets thereon, whereby to insure that successive sheet loaded skids may be continuously removed from the elevator and empty auxiliary skids replaced therein without interruption of the counting and stacking of the sheets, and main and auxiliary conveyor means selectively controlled by said counting device for respectively and successively delivering counted sheets to be stacked to said main and auxiliary skid members.

13. In a sheet counting and stacking machine, the combination of a counting device for counting individual sheets as they are received from a source of supply, a vertically movable elevator disposed in spaced relation to said counting device and carrying a main skid member for receiving a predetermined number of sheets as they are individually counted and for holding them in stacked order, actuating means for said elevator to shift the skid member from one level to another level while receiving counted sheets so that a loaded skid member may be removed from the elevator and an empty auxiliary skid member on said elevator may commence to receive counted sheets without interruption of the counting and the stacking of the sheets, means at one of said levels for periodically lowering said elevator and the skid member carried therein in time with the building up of the stack of sheets on the skid so that the top of the stack will always be in a proper position to receive the counted sheets as they are delivered onto the stack, and conveyor means controlled by said counting device for delivering counted sheets to be stacked to said main and auxiliary skid members.
